SWIVEL FOR ROTATABLE TELEVISION TABLE OR SIMILAR ARTICLE

Carl Krauss, Chicago, Ill.

Application July 3, 1953, Serial No. 25,786

Term of patent 14 years

(Cl. D33—14)

To all whom it may concern:

Be it known that I, Carl Krauss, a citizen of the United States, residing at Chicago, in the county of Cook and State of Illinois, have invented a new, original, and ornamental Design for a Swivel for Rotatable Television Table or Similar Article, of which the following is a specification, reference being had to the accompanying drawing, forming a part hereof.

Figure 1 is a top plan view of a swivel for rotatable television table or similar article embodying my new design;

Fig. 2 is a bottom plan view thereof, but with the top plate rotated through an angle of approximately 45° from the position shown in Fig. 1;

Fig. 3 is an end elevation thereof as viewed from the lower end of Fig. 1; and

Fig. 4 is a horizontal cross sectional view taken in

a plane represented by the line 4—4 of Fig. 1 and viewed in the direction of the arrows.

I claim:

The ornamental design for a swivel for rotatable television table or similar article, substantially as shown.
